G. I. SILBERT.

LOCKING DEVICE FOR LAMP SOCKETS.

APPLICATION FILED OCT. 18, 1912.

1,102,697.

Patented July 7, 1914

UNITED STATES PATENT OFFICE.

GUSTAF I. SILBERT, OF CHICAGO, ILLINOIS.

LOCKING DEVICE FOR LAMP-SOCKETS.

1,102,697.

Specification of Letters Patent.

Patented July 7, 1914.

Application filed October 18, 1912. Serial No. 726,448.

To all whom it may concern:

Be it known that I, GUSTAF I. SILBERT, a citizen of the United States, and a resident of Chicago, in the county of Cook and State 5 of Illinois, have invented certain new and useful Improvements in Locking Devices for Lamp-Sockets; and I do hereby declare that the following is a full, clear, and exact description thereof, reference being had to the 10 accompanying drawings, and to the letters of reference marked thereon, which form a part of this specification.

This invention relates to improvements in locking devices for lamp sockets and consists 15 of the matters hereinafter described and more particularly pointed out in the appended claims.

The object of the invention is to provide means in a lamp socket operable by a key 20 inserted into the socket from the outside thereof for locking a lamp in the socket so that it may not be removed except by the use of a key.

My invention belongs to that particular 25 type of lock socket in which a set-screw is made use of to lock a lamp bulb in the socket and the invention lies in the provision of means which will prevent any possibility of electrical connection between the key and 30 one of the lamp contacts through the set-screw which comprises the locking device.

The advantages of my invention will appear as I proceed with my specification.

In the drawings:—Figure 1 is a view representing a sectional view of a lamp socket provided with my improved locking device, the lamp socket in this case being made of insulating material. Fig. 2 is a view representing a section through Fig. 1, on the line 40 2—2 thereof. Fig. 3 is a view representing a section parallel to that shown in Fig. 2, in a plane indicated by the line 3—3 of Fig. 1. Fig. 4 is a view representing an outside elevation of that part of the socket containing the aperture through which the key is intended to be inserted. Fig. 5 is an elevation of the key. Fig. 6 is a view similar to Fig. 1, showing the construction applied to a socket having a metal shell.

Referring now to that embodiment of my invention illustrated in the drawings and particularly that shown in Figs. 1 to 5, inclusive, 10 indicates the socket which in this case is made of insulating material; 11, the threaded contact shell contained in a recess in said socket in the usual manner; 12 a

lamp bulb, and 13 the threaded shell contact of said lamp bulb adapted for engagement within the contact shell 11 of the socket.

14 indicates an internally threaded sleeve 60 inserted through an aperture in the socket wall and fixed therein in any convenient manner. Said sleeve is made of metal and has threaded into it a plug 15. Said plug 15 has a recess 16 in its end nearest the recess in the lamp socket and in said recess is mounted a pin 17 having an enlarged head 18 of less diameter than that of the recess in the plug, so that an annular insulating air space is left, as shown, between the periphery of said head and the inner surface of the plug 16. The projecting edges of the head 18 are engaged between an insulating disk 19 located in the bottom of the recess 16 and an apertured disk of insulating material 70 20 against which the recessed end of the plug is upset to provide engaging parts 21. By means of this construction the pin is rigidly clamped within the plug and at the same time is insulated therefrom. The head 80 of the plug is provided with diametrically opposite apertures 22 (see Fig. 4) which are adapted to be engaged by pins 23 on the end of a key 24, so constructed that it may be inserted through the outer end of the sleeve 14. As shown, the sleeve 14 has a wall 14^a 85 at its outer end in which is cut an oblong key-hole 25 through which the key may be inserted. The pin 17 being made rigid with the plug 16, as described, it is apparent that by inserting the key with its pins 23 engaged in the holes 22 of the plug, said plug 16 and pin 17 may be rotated together 90 in the manner of a set-screw so as to move said pin toward or away from the contact shell of the lamp bulb. The socket contact shell 11 is provided with an aperture 11^a in line with the pin 17 so that said pin may be brought into direct engagement with the contact shell of the lamp bulb. Although 95 the pin 17 comes into engagement with the contact shell of the lamp bulb and therefore into circuit with one of the lamp terminals, since said pin is entirely insulated from the plug and the sleeve in which said plug is 100 engaged, it is apparent that there is no danger of an electric circuit being maintained through the key to the hand of the one who operates it.

In Fig. 6, my invention is illustrated in 110 connection with a lamp socket having a metallic shell. The construction in this case

is the same as in that just described, the parts being indicated as before. The lamp socket in this case has a metallic shell 10^a.

14^x indicates the sleeve which is provided 5 with an annular flange 14^y secured against the inner surface of the shell 10^a and projecting laterally therefrom, instead of being located in the body of the socket wall as in the case above described.

10 While in describing my invention I have referred to certain details of mechanical construction and arrangement, it is to be understood that the invention is not limited thereto except as hereinafter pointed out in 15 the appended claims.

I claim as my invention:—

1. A locking device for lamp bulbs comprising, in combination with a socket, a recessed shell contact fixed therein provided 20 with an aperture, a lamp bulb having a threaded shell contact adapted to be screwed into the shell contact of said socket, a set-screw having threaded engagement within said socket and projecting through the aperture in said socket contact shell, said set-screw being adapted for engagement with 25 the said threaded shell contact of the lamp, a key adapted to be inserted in the outside

of said socket to rotate said set-screw, and means providing insulation between said 30 set-screw, socket and key.

2. A locking device for lamp bulbs comprising, in combination with a socket, a recessed shell contact fixed therein, provided with an aperture, a lamp bulb having a 35 threaded shell contact adapted to be screwed into the shell contact of said socket, an internally threaded sleeve fixed to said socket adjacent said recess, a recessed plug threaded into said sleeve, a pin fixed in said plug 40 so as to move therewith, means insulating said pin from said plug, and a key adapted to be inserted through the outer end of said sleeve and to be engaged against the outer end of said plug to bring said pin into engagement through the aperture in said 45 socket shell with said contact shell of the lamp.

In testimony, that I claim the foregoing as my invention I affix my signature in the presence of two witnesses, this 15th day of October, A. D. 1912.

GUSTAF I. SILBERT.
